US0D1080557S

(12) **United States Design Patent** (10) **Patent No.:** **US D1,080,557 S**
(45) **Date of Patent:** **** Jun. 24, 2025**

(54) **DATA CABLE**

(71) Applicant: **Shenzhen Mfish Cultural Technology Co., Ltd.**, Shenzhen (CN)

(72) Inventor: **Qixuan Zhang**, Shenzhen (CN)

(73) Assignee: **Shenzhen Mfish Cultural Technology Co., Ltd.**, Shenzhen (CN)

(**) Term: **15 Years**

(21) Appl. No.: **29/992,516**

(22) Filed: **Mar. 10, 2025**

Related U.S. Application Data

(62) Division of application No. 29/973,389, filed on Nov. 15, 2024.

CLAIM

The ornamental design for a data cable, as shown and described.

DESCRIPTION

FIG. 1 is a front, right and top perspective view of a data cable, showing my new design;

FIG. 2 is a rear, left and bottom perspective view thereof; FIG. 3 is a perspective view thereof, shown in a used condition;

FIG. 4 is a front view of FIG. 1;

FIG. 5 is a rear view thereof;

FIG. 6 is a left side view thereof;

FIG. 7 is a right side view thereof;

FIG. 8 is a top plan view thereof; and,

FIG. 9 is a bottom plan view thereof.

The broken lines shown in the drawings illustrate portions of the data cable that form no part of the claimed design.

1 Claim, 9 Drawing Sheets
